SAMUEL S. HARGRAVES, STEPHEN DE ORLOW, AND JAMES W. WILFORD, OF LANSING, MICHIGAN, ASSIGNEES, BY MESNE ASSIGNMENTS, TO MELLING FORGING COMPANY, OF LANSING, MICHIGAN, A CORPORATION OF MICHIGAN

AIR INTAKE DEVICE

Application filed February 20, 1928. Serial No. 255,626.

The present invention pertains to a novel construction applicable to engines of the type employing a gaseous fuel mixed with air, for the purpose of separating solid particles from such air before it is drawn into the carbureter.

This operation is accomplished by novel attachments to the fan which act on the air current thereof in such a manner as to leave the solid particles behind and permit the clean air to enter the intake pipe. The invention may take several forms, two of which are described in the following specification and in the accompanying drawing, in which—

15 Figure 1 is a side elevation of a gasoline engine showing the device of the invention applied thereto and illustrated in longitudinal section; and

20 Fig. 2 is a section on the line 2—2 of Figure 1.

Reference to these views will now be made by use of like characters which are employed to designate corresponding parts throughout.

25 In Figure 1 is illustrated a gasoline engine 1 of conventional construction having a carbureter 2 and an air intake pipe 3 leading from the front end thereof.

30 According to the present invention the inlet end of the pipe consists of a cylindrical head 4 closed at the rear end by a disk 5 having an inwardly extending boss 6. Into the front end is fitted a collar 7 having radial arms 8 which support another boss 9 in alignment with the member 6. To the collar 7 is applied a casting comprising a hollow pulley 10 having at its front end a skirt 11 and a number of radial arms 12 which support an integral and inwardly extending sleeve 13.

35 A cup 14 extends forwardly from the sleeve and is provided with an outer flange 15 to which the fan 16 is secured by bolts 17.

40 Within the hub 13 is mounted a shaft 18 having a reduced end 19 received in the aligned

members 6 and 8. Bushings 20 are interposed between the shaft and hub, and the forward end of the shaft has a flange 21 engaging the adjacent bushing, whereby the assembly may be clamped by a nut 22 threaded on the other end of the shaft. The forward end of the shaft has a longitudinal bore 23 communicating with a diametrical bore 24 which in turn communicates with the space between the two bushings 20. At one of the radial arms 12 is formed an oil duct 25 communicating with the cup 14 and thus adapted to supply oil inside the hub 13. At the inner end of the hub is provided a packing 26 retained by a cap 27.

50 Between the flange 15 and the fan 16 is secured the base of a deflector formed as a cup 28 overlapping the skirt 11 and spaced therefrom in order to provide a passage from the atmosphere into the skirt. The deflector surface extends from the fan towards the engine and flares outwardly with respect to the pulley assembly.

55 In the operation of this device, rotation of the fan drives the current of air towards the engine in the usual manner. The deflector, however, due to the shape already described, causes the current to flow away from the pulley assembly as indicated by the arrows in Figure 1. The suction in the 60 intake pipe 3 induced by the cylinders acts through the skirt 11 and interior of the deflector upon this current of air. The suction draws on the air current but, because of the deflected movement of the latter, fails 65 to attract the dust particles therein and consequently sucks comparatively clean air into the pipe 3. A filtering action of the intake air is thus effected, and the necessity of a breather or other filter in advance of the 70 carbureter is overcome.

75 Although a specific embodiment of the invention has been illustrated and described, it will be understood that various alterations in the details of construction may be made with- 80

out departing from the scope of the invention as indicated by the appended claim.

What we claim is:

In combination with the fan and air intake pipe of a gas engine, said pipe having an open end in the air stream of said fan, a cup-shaped deflector having one end secured to said fan and its other end spaced around the open end of said intake pipe.

10 In witness whereof we affix our signatures.

SAMUEL S. HARGRAVES.

STEPHEN DE ORLOW.
